United States Patent Office.

A. A. DOW, OF GLENHAM, NEW YORK.

Letters Patent No. 95,208, dated September 28, 1869.

IMPROVEMENT IN FEEDING-MECHANISM FOR CARDING-ENGINE.

The Schedule referred to in these Letters Patent and making part of the same.

To all whom it may concern:

Be it known that I, A. A. Dow, of Glenham, in the county of Dutchess, and State of New York, have invented a new and improved Feeding-Apparatus for Carding-Machines; and I do hereby declare that the following is a full, clear, and exact description thereof, which will enable others skilled in the art to make and use the same, reference being had to the accompanying drawings, forming part of this specification.

The object of this invention is to provide certain improvements in the Apperly and Clissold diagonal feed for second breakers and finishers, calculated to make the same more efficient than as at present arranged.

The invention consists in providing the toothed or spiked feeding-strap on the short side of the said feeding-device with the operating-devices hereinafter described, having "positive" movements; also in providing the rollers of the traveller, which lays the roping, with the means hereinafter described, for operating them positively.

Figure 1 represents in red a plan view of the said feeding-apparatus, with my improvements attached, and shown mostly in black;

Figure 2 represents a front elevation of the same;

Figure 3 represents a side elevation of my improved arrangement of means for operating the said short toothed feeding-belt;

Figure 4 represents a plan view of the same;

Figure 5 represents a plan view of the traveller; and

Figure 6 represents an elevation of the same.

Similar letters of reference indicate corresponding parts.

A short toothed belt, A, is employed on the short side of this feeding-apparatus, above the carrying-belts, and the roping, designed to insure a steady and uniform movement of the looped ends of the roping, which are otherwise liable to be arrested, and separated in one part and pressed together in another, resulting in uneven edges in the bats.

This belt is now operated by a driving-pulley at one end, and works over a tension-pulley at the other, and owing to being so short, it works badly in this way, very often slipping and aggravating the evil it is designed to overcome; to obviate which, I propose to provide the hub of the driving-pulley B with a toothed

wheel, C, and in like manner the hub of the tension-pulley E with another toothed pinion, F, and on the axles of each I arrange a cast-metal or other support, G, for an intermediate toothed wheel, H, gearing into each, whereby the motion of one is "positively" dependent upon the other, and the belt insured against slipping.

For adjusting the tension-pulley and the intermediate wheel H relatively thereto, the end of the support G of the intermediate wheel is slotted where the axle of the said pulley passes through it, and the stud-pin of the wheel H is adjustable in a curved slot, I.

In the common arrangement, the laying-rollers K of the travellers are dependent for their rotary motion upon their frictional contact with the smooth face of the bar L, which, owing to various causes, is not perfectly reliable, and they sometimes fail to revolve, which works great damage, owing to the delicate nature of the roping, which is thereby laid very irregularly, producing irregularities in the bats. Therefore, I propose to form cog-teeth on the face of the bar L, and corresponding teeth on the upper ends of the rollers gearing into them, as shown at M N; and to prevent the roping or fibres thereof from working up into the said teeth, I interpose the plate O between the working-parts of the said rollers and the toothed parts.

I propose also in some cases to use a chain and chain-wheels for operating the pulleys of the said feed-belt A, the said chain and wheels being arranged with recesses and projections, to prevent slipping.

Having thus described my invention,

I claim as new, and desire to secure by Letters Patent—

1. The combination, with the short toothed belt A, of the diagonal feeding-mechanism herein described, of the geared pulleys B E, intermediate wheel H, and slotted support G, all arranged substantially as specified.

2. The arrangement with the laying-traveller of the toothed rollers K, toothed rack M, and guard-plate O, all substantially as specified.

A. A. DOW.
